SUCTION CLEANER

David Van Maldeghem and William J. Ollinger,
New York, N. Y.

Application October 5, 1931. Serial No. 566,853

3 Claims. (Cl. 15—6)

The invention relates to cleaners of the suction type and has for its main object to provide a device by means of which kapok, feathers, cotton, floss and other materials employed for filling or stuffing mattresses, pillows, cushions, quilts and other articles, may be readily and speedily removed from the surface of such articles after they have been filled or stuffed. Another object is to provide means for the expedient collection and removal of the substances removed. A further object is to so construct the brushes employed in the machine that any substance adhering to them may be readily removed. A still further object is to provide a machine of simple and inexpensive construction, which will occupy but small floor space, which requires no skill to operate, and which can be operated at very low cost.

These and other objects and advantages will be readily understood from the following description and from the accompanying drawing of a preferred embodiment in which, however, modifications may be made without departing from the scope of the appended claims. In the drawing

Fig. 1 is a front elevation of the preferred embodiment of the cleaner with a certain part shown broken away to expose the interior,

Fig. 2 is a side elevation,

Fig. 3 a cross-sectional side elevation taken on line 3—3 in Fig. 1, and

Fig. 4 an end view of one of the brushes employed.

Referring now to all the views, simultaneously, the machine consists of a pair of side frames 10 and 11 which are spaced apart and connected by tubes 12, 13, 14 and 15. The general contour of the side frames is plainly shown in Figs. 2 and 3, as are also the locations of the tubes. The front sides of the upper ends of the frames are curved and to these parts a curved plate 16 is secured. It is provided with a rectangular opening 17, as shown, across which a plurality of rods 18 are placed.

The lower cross member 19, of the side frame 10, is provided with a vertical socket in which a bar 20 is clamped by a set screw 21. A platform 22 is provided at the upper end of the bar and on this an electric motor 23 is securely bolted. The motor drives a suction fan 24 which is preferably suspended from the tubes 12 and 13 by means of bosses 25 and 26, but may, of course, be constructed and supported in any other suitable manner. The air-intake opening 27 of the fan is located inside one end of a receptacle 28, while the air-outlet 29 is turned towards the rear of the machine. A chute 30 extends upwardly from the

receptacle 28 and its upper end is connected with the plate 16 so that the fan will draw air through the opening 17. The chute is of the same width as the opening.

A pulley 31 is mounted on the motor shaft which, by means of a belt 32 and another pulley 33, drives a shaft 34 on which a rotary brush 35 is removably mounted. We prefer to support the shaft 34 in a pair of bearings 36 which are placed on opposite sides of the chute and to provide means on these sides of the chute for cleaning purposes.

The pulley 33 is preferably mounted to rotate on the shaft 34 if the brush should accidentally catch in the material operated on. A friction clutch 38, of any standard spring-actuated type is pinned to the shaft and exerts sufficient friction against the pulley to drive the shaft under ordinary conditions. A stationary shaft 39 is mounted below the opening 17 and on this shaft a plurality of flexible beaters 40 are secured. Another shaft 41 is rotatably mounted above the opening 17. It rotates in bearings 42 which are located on opposite sides of the chute and is provided with a plurality of catches 43 which engage with the ends of the beaters. This shaft is driven from the shaft 34 by means of any suitable train of gears such, for example, as shown at 44 and it rotates at a much lower speed than the brush shaft.

The machine operates in the following manner: It is well known that a pillow, mattress or other article after being filled or stuffed will have particles of the filling material adhering to its outer side which must be removed. When the motor 23 is started the fan creates a suction through the opening 17 and if now a pillow, or other article, covered with particles of the filling material is placed upon the plate or table 16, the part covering the opening will be freed of these particles by the suction through this opening. By moving the article in front of the opening it is evident that it may be entirely cleaned.

As certain filling materials adhere more tenaciously than others, the brush 35 is provided. The brush loosens the particles which are then readily carried off by the suction. The rods 18 prevent the article from being drawn too far into the opening. The particles removed are drawn down through the chute and into the receptacle 110

from whence they are drawn through the fan. Bags may be attached to the air outlet 29 for collecting the particles removed.

To increase the speed with which an article 5 may be cleaned, the beaters 40 are provided. These beaters, which are normally straight, are engaged by the catches 43 so that their ends are drawn back and released, as plainly shown in Fig. 3 where the dotted position shows a beater after 10 it is released. The beaters are interposed between the tufts of hair in the brush so as not to interfere with these. As the beaters apply rapid blows to the article operated on, the particles adhering thereto are loosened and so readily re- 15 moved.

As some of the filling materials used, particularly if consisting of long fibres, have a tendency to twine around the brush and work down towards the brush body to stick firmly there, a 20 plurality of grooves 45 are milled in the brush body, as shown in Fig. 4. To remove this adhering material a sharp knife is run lengthwise of the grooves to cut it, after which it is easily removed. While a brush having four straight rows 25 of hairs has been illustrated, it will be understood that brushes of other constructions are employed according to the material operated on. The brushes are therefore made interchangeable.

The foregoing will show that the device is very 30 simple in its construction and that no special skill is required to operate it. While the machine has been described for use on filled or stuffed material or articles, it is evident that it may be used on many other articles. For this reason we 35 do not wish to limit the invention to any particular use only.

Having described our invention and its operation, what we claim and wish to protect by Letters Patent is:

40 1. In a suction cleaner of the class described; a frame structure; a plate located at the upper part of the frame structure for supporting the articles to be cleaned; an aperture formed in said plate; a duct leading from said aperture; a rotary brush located within said duct, adjacent to said aperture, for brushing the articles passed over the aperture; the bristles of said brush arranged in spaced, cylindrical rows; a plurality of flexible beaters also located within said duct, transversely with and in close proximity to said aperture, for beating the articles passed over the aperture; said beaters interposed between the rows of bristles of the brush; one end of each of said beaters secured to a stationary shaft located sub- 45 stantially behind one edge of the aperture; a rotating shaft located behind the opposite edge of the aperture; a plurality of catches secured on 50 said rotating shaft; the free ends of said beaters engaged and flexed by said catches; an exhaust fan connected with the duct; and means for actuating said rotating shaft, said rotary brush, said rotary shaft, and said fan.

55 said rotating shaft; the free ends of said beaters engaged and flexed by said catches; an exhaust fan connected with the duct; and means for actuating said rotary brush, said rotary shaft, and said fan.

60 2. In a suction cleaner of the class described; a frame structure; a plate located at the upper part of the frame structure for supporting the articles to be cleaned; an aperture formed in said plate; a plurality of spaced bars secured across said aperture; a duct leading from said aperture; a rotary brush located within said duct, adjacent to said aperture, for brushing the articles passed over the aperture; the bristles of said brush arranged in spaced, cylindrical rows; a plurality of flexible beaters also located within said duct, transversely with and in close proximity to said aperture, for beating the articles passed over the aperture; said beaters and said bars alternately interposed between the rows of bristles of the brush; one end of each of said beaters secured to a stationary shaft located substantially behind one edge of the aperture; a rotating shaft located behind the opposite edge of the aperture; a plurality of catches secured on said rotating shaft; the free ends of said beaters engaged and flexed by said catches; an exhaust fan connected with the duct; and means for actuating said rotary brush, said rotary shaft, and said fan.

65 3. In a suction cleaner of the class described; a frame structure; a plate located at the upper part of the frame structure for supporting the articles to be cleaned; an aperture formed in said plate; a plurality of spaced bars secured across said aperture; a duct leading from said aperture; a rotary brush located within said duct, adjacent to said aperture, for brushing the articles passed over the aperture; the bristles of said brush arranged in spaced, cylindrical rows; a plurality of flexible beaters also located within said duct, transversely with and in close proximity to said aperture, for beating the articles passed over the aperture; said beaters and said bars alternately interposed between the rows of bristles of the brush; one end of each of said beaters secured to a stationary shaft located substantially behind one edge of the aperture; a rotating shaft located behind the opposite edge of the aperture; a plurality of catches secured on said rotating shaft; the free ends of said beaters engaged and flexed by said catches; an exhaust fan connected with the duct; friction clutch controlled means for actuating said rotary brush and said rotary shaft; and means for rotating the fan.
